UNITED STATES PATENT OFFICE

152,688

DESIGN FOR A CLOTHES HANGER

Harry S. Hammond, Garden City, N. Y.

Application May 27, 1947, Serial No. 139,313

Term of patent 3½ years

(Cl. D33—8)

To all whom it may concern:

Be it known that I, Harry S. Hammond, a citizen of the United States of America, residing at Garden City, in the county of Nassau and State of New York, have invented a new, original, and ornamental Design for Clothes Hanger, of which the following is a specification, reference being had to the accompanying drawing, forming part thereof.

Fig. 1 is a perspective view;
Fig. 2 is a side view;
Fig. 3 is a rear view, and
Fig. 4 is a top view of a clothes hanger showing my new design.

I claim:

The ornamental design for a clothes hanger, substantially as shown.

HARRY S. HAMMOND.
